UNITED STATES PATENT OFFICE.

BEADON R. LYDDON, OF SYCAMORE, ILLINOIS.

LAND-ROLLER.

SPECIFICATION forming part of Letters Patent No. 372,984, dated November 8, 1887.

Application filed October 7, 1886. Serial No. 215,634. (No model.)

To all whom it may concern:

Be it known that I, BEADON R. LYDDON, a citizen of the United States, residing at Sycamore, in the county of De Kalb and State of Illinois, have invented a certain new and useful Improvement in Land-Rollers, which is fully set forth in the following specification, reference being had to the accompanying drawings, in which—

- 10 Figure 1 is a side elevation of a land-roller embodying my invention; Fig. 2, a transverse sectional view of the same, taken on the line $x x$ of Fig. 1; Fig. 3, a rear elevation of the same, and Fig. 4 a detail elevation of one of 15 the segments detached.

Like letters refer to like parts in all the figures of the drawings.

My invention relates to land-rollers, and has for its object to produce a land-roller which 20 shall be simple and strong in its construction, and which shall effectually level the ground and crush the clods; and to these ends my invention consists in certain novel features, which I shall now proceed to describe, and will then 25 particularly point out in the claims.

In the drawings, A represents the main frame, which is rectangular in form, consisting of transverse members a and longitudinal members a' , these latter being curved or arched, 30 as shown in Fig. 1 of the drawings, to pass over the wheel-segments.

B represents the tongue, and C the driver-seat, which are attached to the frame A in any suitable manner. At each end of the main 35 frame there is secured, to the under side thereof, a yoke or bracket, D, and in these yokes or brackets is mounted a fixed axle, E, each yoke being provided with a hub portion, d , through which the said axle passes. The 40 axle E is additionally supported at its center by means of a yoke or bracket, D', secured to the main frame A, and having a suitable hub, d' , through which the said axle passes. Upon the axle E is mounted a series of wheel-segments, F, each consisting of a hub, f , mounted on the axle, spokes f' , and a rim or tire, f'' , of considerable thickness and of a width equal 45 to the width of the hub f' . Each wheel-segment is provided upon its outer periphery with a series of circumferential ribs or projections, f^3 , preferably V-shaped in cross-section, as shown. In the present instance I have

shown twelve of these wheel-segments mounted upon the axle E and each provided with a series of three ribs, f^3 . The wheel-segments are 55 capable of independent rotation upon the axle E, but are practically in contact with each other, only sufficient space or play being left between them to prevent binding.

G represents a bar pivoted to the rear of the 60 frame A and provided with a series of scrapers, H, equal in number to the number of wheel-segments employed—being twelve in the present instance. Each scraper H is provided with a series of notches, h , equal in number 65 and conforming in shape to the ribs f^3 on the wheel-segments F.

G' represents a lever attached to the bar G and extending upward, so as to be within convenient reach of the occupant of the seat C. 70

The operation of my improved land-roller will be readily understood from the preceding description. When drawn across the surface of the soil, the wheel-segments will revolve and, by means of their circumferentially-ribbed 75 peripheries, will effectually crush the clods and pulverize the soil, thereby preparing the same for the reception of crops. The wheel-segments, being capable of independent revolution, will permit the entire device to be 80 turned in a very small space, and consequently to be operated in corners and elsewhere with great convenience. If the soil adheres to the rollers in too great quantities and clogs the same, it may be readily removed by means of 85 the scrapers H, which are operated in an obvious manner through the bar G and lever G'. Moreover, since the scrapers H are independent, any one of them if broken or worn out may be renewed at a slight cost without involving the removal or loss of the remaining 90 ones.

It is obvious that various modifications in the details of construction may be made without departing from the principle of my invention, and I therefore do not wish to be understood as limiting myself strictly to the precise details hereinbefore described, and shown in the drawings.

Having thus described my invention, what I 100 claim as new, and desire to secure by Letters Patent, is—

1. In a land-roller, the combination, with the main frame A, the brackets D, having

hubs d , and the bracket D' , having hub d' , of the fixed axle E , mounted in said hubs and extending from one side of the machine to the other, and the independent wheel-segments F , mounted loosely on said axle and having hubs f and rims f^2 , of equal width, connected by spokes f' , each segment being provided with a series of circumferential ribs, f^3 , substantially as and for the purposes specified.

2. In a land-roller, the combination, with the independently-revolvable wheel-segments F , each provided with a series of circumfer-

ential ribs, f^3 , of the bar G , pivoted to the main frame and provided with lever G' , and a series of separate scrapers, H , independently attached to said bar, and each provided with a series of notches, h , corresponding to the circumferential ribs, substantially as and for the purposes specified.

BEADON R. LYDDON.
